UNITED STATES PATENT OFFICE.

LYMAN E. DODGE, OF MORRISTOWN, NEW JERSEY.

SEMIAUTOMATIC TRAIN CONTROL.

Application filed March 21, 1922, Serial No. 545,564. Renewed January 9, 1925.

To all whom it may concern:

Be it known that I, LYMAN E. DODGE, a citizen of the United States, and a resident of the city of Morristown, in the county of Morris and State of New Jersey, have invented a new and useful Semiautomatic Train Control, of which the following is a specification.

This invention relates to automatic train control and more especially to a system of automatic train control in which it is necessary for the train driver to take appropriate action whenever the train passes an indication point on the roadway, and for that reason has been denominated by me a semi-automatic train control.

The principal object of this invention is the production of a train control system which will so act that it will operate to impose a gradually decreasing maximum permissible speed on the train after passing an indication point in the roadway, whether or not the indication from the roadway is equivalent to a full clear signal or a caution signal unless the train driver at the appropriate moment performs a manual operation on the train, so that even if the equipped vehicle passes an indication on the trackway, which would be equivalent to a full clear signal on the train, if properly accepted by a manual operation of the engine driver, nevertheless, if this manual operation is not performed, the train will be brought to a stop before proceeding so far as to cause a collision, as for instance with a train ahead.

It is also an object of this invention to provide a system by which the driver, after a caution signal has been passed, or when he has approached to within a substantially maximum braking distance from a preceding train will be obliged to gradually decrease the speed of the train, so that it will be brought to a stop or a minimum low speed before reaching the danger point ahead, or upon his failure to so do, to cause an automatic application of the air brakes of the train.

A further object of the invention is to provide a system such that the driver while gradually reducing speed in obedience to a caution signal, must at appropriate times perform manual operations, and upon his failure so to do, then the system is so designed that the air brakes will be applied regardless of the speed of the train.

Other objects and advantages will appear as the description of the particular physical embodiment selected to illustrate the invention progresses, and the novel features of the invention will be particularly pointed out in the appended claims.

In describing the invention in detail, and the particular physical embodiment selected to illustrate the invention, reference is had to the accompanying drawings, wherein I have illustrated a particular preferred physical embodiment of my invention, and wherein like characters of reference designate corresponding parts throughout the several views, and in which:

Fig. 1 is a schematic illustration of a somewhat conventional track and associated signals to which the trackway portion of my invention has been applied;

Fig. 2 is a schematic illustration of the mechanism required by my invention as positioned upon a movable vehicle;

Fig. 3 is a fragmentary sketch of a detail as shown by Fig. 2;

Fig. 4 is a fragmentary sketch of a detail as shown by Fig. 2.

Referring particularly to Fig. 1, numerals 1 designate the two rails of a trackway. These rails are separated into electrically isolated sections by the insulating joints as 2. Each electrically isolated section has at one end a battery 3 connected across the rails and at the other end a relay, as 4, connected across the rails.

Opposite each of the insulating joints are located signals as 5, 6 and 7. These signals may be controlled in any usual and customary manner, as is well understood by those skilled in the railway signalling art, and in the diagram I have shown them in such positions that when signal 7 is at danger as shown, then signal 6 is at caution and signal 5 is at full clear, this condition being caused by the presence of the train 8 on the track circuit section just in advance of signal 7, as is well understood by those skilled in this art.

About opposite each of the signals, but far enough back of the insulating joints 2 so that the wheels of a train moving in the direction of traffic, that is, in the direction of the arrow A, will not have passed upon the two track rails in advance of a signal before a device on the vehicle, to be herein-after described, comes into proper co-operative relation therewith, I have positioned

electromagnetic devices as 9, 10 and 11. Each of these electromagnetic devices consists of a core of laminated iron, having each end pointing upwardly and having 5 coils as 12, 13 and 14 wound on the central portion thereof. Each of these coils is connected with a circuit in such a manner that the coil just back of the danger signal is de-energized as is also the coil just back of 10 the caution signal, but the coil just back of a clear signal is energized. The circuit including a coil as 12 may be traced on Fig. 1 as follows: one brush of the alternating current generator 15, wire 16, coil 12, wire 15 17, armature 18, wire 19, armature 20, and wires 21 and 22 back to the other brush of the alternating current generator 15. This circuit is closed because relay 4, at signal 5 is energized and relay 4 at signal 6 is energized, because there is no train on either the 20 section just in advance of signal 5, or just in advance of signal 6. It should be observed, however, that the exactly similar circuit of coil 13 is open at relay armature 23 25 of relay 4 at signal 7, due to the presence of the train 8 on the section just in advance of signal 7, and that the coil 11 is in an open circuit by reason of the fact that the armature 24 of relay 4 at signal 7, is in the lower 30 position due to the presence of the train 8 on the section just in advance of the signal 7.

It is now apparent that a train passing over the trackway, as illustrated by Fig. 1, 35 in the direction of the arrow A, will pass over an electromagnetic device 9 at the clear signal 5, which will be generating a magnetic flux, but that the same train will pass over an electromagnetic device 10 at signal 6 and an electromagnetic device 11 at signal 7, which are not generating a magnetic flux.

Let it now be assumed that a vehicle represented generally by V of Fig. 2, moves over the trackway illustrated by Fig. 1, in 40 the direction of the arrow A and that it approaches and passes over the electromagnetic device 9. Under such conditions, the device 9 illustrated in Fig. 2 as being connected directly to an alternating current generator 25, the circuit of which is closable by hand switch 26 generates a magnetic flux which finds its most appropriate path through the laminated iron core 27 hung in any appropriate or suitable manner from 45 the vehicle as from the axle 28 as shown. The magnetic flux flowing through core 27 generates in coil 29 a current if the coil is connected to a circuit which is completed.

On the vehicle a conducting block 30 is 50 positioned and connected to a stem 31 on the end of which is a button 32, which is spring pressed by the spring 33 to the position as shown, but if at the moment the core 27 passes the electromagnetic device 9, the button 32 is being pressed by the driver

of the vehicle, then the block 30 connects the contacts 34 and 35. Under these circumstances, a complete circuit is formed including the coil 29 on the core 27, which circuit is as follows: one terminal of coil 29, wire 36, electromagnet 37, wire 38, contact 34, block 30, contact 35, and wire 39 back to the other terminal of the coil 29. The current flowing in the above-traced path energizes the electromagnet 37, and causes it to 55 lift its armature 40, which being connected to a sleeve 41, surrounding shaft 42, causes shaft 42 together with worm 43 attached to the end thereof to be raised out of mesh with worm wheel 44, this being possible by 60 reason of universal joint 45 in shaft 42. The worm 43 being lifted out of mesh with the worm wheel 44, allows that wheel by reason of weight 46, connected thereto, by cord 47, to be rotated clockwise until the stop 48 65 comes in contact with the abutment 49. This return movement of worm wheel 44 is almost instantaneous, and it must be, because the circuit through electromagnet 37 is of very short duration, so that although worm 43 is raised, it almost immediately thereafter drops into mesh with worm wheel 44. As soon as 43 drops into mesh with 44, 44 begins to turn in the direction of the arrow B, because shaft 42 through universal joint 45, 70 is connected to bevel gear 50, which meshes with bevel gear 51, rigidly attached to shaft 52, which at its lower end, has a beveled gear 53, rigidly attached thereto, meshing with beveled gear 54, attached to axle 28. Consequently as the train is moving, the wheels and axle are turning, and shaft 52 transmits motion to the train of mechanism just described, so that worm wheel 44 rotates in the direction of the arrow B. 75

On the same shaft 55, upon which worm wheel 44 is mounted is a pinion 56, meshing with a rack 57, so that as worm wheel 44 rotates in the direction of the arrow B the rack 57 moves longitudinally in the direction of the arrow C, and causes the pinion 58 to revolve in a counter clockwise direction as viewed in Fig. 2. Attached to the same shaft to which pinion 58 is rigidly attached is a pointer 59, perhaps preferably 80 colored red. This pointer starts to rotate in a counter-clockwise direction as viewed in Fig. 2 as soon as rack bar 57 starts to move longitudinally in the direction of the arrow C, but the operator or driver of the vehicle cannot observe this movement because of the shield 60, placed in front of the pointer 59 until the pointer has traveled to such an extent that it appears to the left of the shield as viewed in Fig. 2, that is, 85 when it would be pointing to the 60-miles per hour mark. The pointer 59 would not appear from behind the shield until the train or vehicle after passing signal 5 had reached signal 6, that is, pointer 59 would be ob- 90

scured all of the time while the vehicle was traveling in the full clear block, this being due to the proportioning between the diameter of the wheels of the vehicle, the train 5 of mechanism connecting the axle with worm wheel 44, the size and number of teeth of pinion 56, rack 57, and pinion 58, and the particular positioning of pointer 59 upon the spindle to which pinion 58 is attached.

10 From the above it will be seen that a train moving in the direction of the arrow A on the trackway as shown in Fig. 1, would, if the driver pushed the button 32, at the time he passed electro-magnetic device 15 9, receive an impulse which would cause worm 43 to be lifted allowing 44 to return to normal position and then worm 43 dropping again into mesh with worm wheel 44, would cause worm wheel 44 to rotate, causing through a train of mechanism, the pointer 59 to be moved counterclockwise, but the movement would not be observable by the driver until pointer 59 had reached the indication of 60 miles per hour, at which time 20 25 the train would have reached signal 6, and would be about to enter a caution block, that is, a block through which the speed of the train must be gradually decreased so that the train would arrive at signal 7 at 30 not more than a safe speed, say 0 miles per hour, or 10 miles per hour.

If the train, when it passes electromagnetic device 10, receives through its core 27 a 35 magnetic flux, and the driver is pushing button 32 at the proper time, then worm 43 would be raised out of mesh with worm wheel 44 and the same operations would take place as have just been described, but if no magnetic flux is generated by electromagnetic device 10 when the train passes there- 40 over, the worm 43 will remain in mesh with worm 44, and continue to turn the same in the direction of the arrow B, and the pointer 59 would gradually move counter-clock- 45 wise and indicate the proper permissible speeds at which the train should be driven through the caution block, these speeds being indicated as gradually reducing to any given minimum, even to zero, but illustrated 50 in Fig. 2 as being reduced gradually to 10 miles per hour at which point the cut-away portion 61 of worm wheel 44 comes beneath worm 43 and no further movement of worm wheel 44 is effected. Consequently, no 55 further movement of pointer 59 is caused, so that the pointer never indicates less than a minimum permissible speed of, say, ten miles per hour.

Moving over the same graduated dial as 60 the pointer 59 is a pointer 62, which pointer 62 is fixed to a pinion 63 moved by the toothed end of lever 64, pivoted at 65, and movable in exact accordance with the actual speed at which the vehicle is proceeding, be- 65 ing moved by 84, so that the hand 62 at all

times indicates the actual speed of the vehicle. Consequently, if the driver keeps the black hand 62 just ahead, in a counter-clockwise direction, of the pointer 59, while passing through the caution block from signal 6 to signal 7, he is maintaining an actual speed of the train which is perfectly safe, and will enable him at all times to stop before arriving at the signal 7 just in advance of which is located the train 8.

70 Although the driver of a train is supposed to at all times regulate the speed thereof, properly in accordance with indications transmitted to him, nevertheless it has been found that he cannot always be depended upon to do this, either because, as in the extreme case he may suddenly die, or he may be inattentive or actually negligent, or even criminally careless, so that although the pointers 59 and 62 indicate to an engineer just exactly what he should do in order to be safe, it is necessary in addition to these to have other mechanisms which will actually stop the train if he fails to act in accordance with the indications presented to 75 him.

In order to effectuate this latter purpose, applicant has provided the electropneumatic valve 66, controlling in any usual way the venting of an air brake train pipe 67. Normally this electropneumatic valve has a circuit closed therethrough, to maintain it energized and thereby prevent venting of the train pipe. The circuit for energizing valve 66 is as follows: one terminal of the 80 battery 68, wire 69, contact 70, connector 71, contact 72, wires 73 and 74, contact 75, connector 76, contact 77, wires 78, 79, and 80, valve 66 and wire 81 to the other terminal of the battery 68. This circuit normally maintains the valve 66 energized and so prevents venting of the train pipe and setting the brakes. There are, however, two contacting devices in this circuit; one includes the connector 71 and the other the 85 connector 76. The connector 71 is connected directly to the rod or bar 82, which is bifurcated at its end and straddles the reduced portion 83 of the movable sleeve 84 of a fly ball device indicated as a whole by 90 G. This fly ball device is driven from shaft 52, and is so arranged that as the speed of the vehicle increases the member 84 moves in the direction of the arrow D, so that rod 82 is also moved in the same direction, carrying with it connector 71, and the contacts 70 and 72 are of such length that they are connected by connector 71 from 0 miles 95 per hour just so long as the actual speed of the train does not exceed a fixed maximum, such for instance as 60 miles per hour. The other connector 76 in the circuit valve 66, spans two contacts 75 and 77, and is itself rigidly connected to and moved 100 with the rack bar 57, and is so positioned 105 with the rack bar 57, and is so positioned 110 with the rack bar 57, and is so positioned 115 with the rack bar 57, and is so positioned 120 with the rack bar 57, and is so positioned 125 with the rack bar 57, and is so positioned 130

on the rack bar 57 in relation to contacts 75 and 77, that it spans these contacts 75 and 77 and electrically connects the same all of the time while the vehicle is traveling throughout a full clear block as from signal 5 to signal 6. It will thus be seen that if at any time the driver exceeds the fixed predetermined maximum permissible speed, the electropneumatic valve 66 will be deenergized, because connector 71 will be moved out of contact with contacts 70 and 72 and also that all of the time the train is traveling from signal 5 to signal 6 as illustrated in Fig. 1, the circuit of the valve 66 through connector 76 will be closed, but at the moment the train passes signal 6, the connector 76 moves out of contact with contacts 75 and 77, so that unless there are other means for closing the circuit between wires 79 and 74, the valve 66 will be deenergized. The other means for closing this circuit is the connector 85, attached to rack bar 57, and so attached that just before 76 moves out of contact with 75 and 77, 85 moves into contact with the contacts 86 and 87, and this as is evident occurs at the instant the train passes the signal 6, shown in the caution position in Fig. 1.

It will be evident by an inspection of Fig. 2, that all of the time while connector 76 connects 75 and 77 that connector 85 connects 89 and 90, and, consequently, keeps a signal, such for instance as a white lamp 91, lighted through battery 92. This can be taken to indicate that 76 has not moved out of contact with 75 and 77, and consequently, 85 has not moved into contact with 86 and 87, or it may be interpreted as meaning that the vehicle is still traveling in the full clear or unrestricted speed section. As soon however as 76 moves out of contact with 75 and 77, then 88 moves into contact with 93 and 94, and consequently, the signal such for instance as a red lamp 95, is lighted by reason of battery 96, which can be taken to indicate that 85 connects 86 and 87, or that the train or vehicle has entered the caution or restricted speed block or section, that is, the train is moving from signal 6 to signal 7 and must gradually reduce speed.

After the vehicle passes signal 6, moving in the direction of the arrow A, and after failing to receive a magnetic flux from electromagnetic device 10, as it proceeds, the pointer 59 moves gradually counter-clockwise, and the member 85 moves in the direction of the arrow C. After a certain distance traveled by the train under these conditions, the member 85 will pass off of contact 87, and onto contact 97, and this will result in deenergizing the valve 66 unless in the meantime a button, as 98, has been pressed by the driver of the vehicle. This is so because when the circuit for the valve 66 was opened at connector 76, it was closed by connector 85, so that current flowed through the valve 66 in a circuit as follows: one terminal of the battery 68, wire 81, valve 66, wires 80, 79 and 99, contact 87, connector 85, contact 86, wires 100 and 73, contact 72, connector 71, contact 70 and wire 69 back to the other terminal of the battery 68.

The current flowing in the above-traced path maintains the energization of valve 66 after the breaking of the connection between 75 and 77, but when connector 85 moves out of contact with contact 87, the last traced circuit is then broken, and the valve 66 would be deenergized if another circuit were not formed. This other circuit is formed by the contact of 85 with contact 97 and by the pushing of button 98, which causes a connection between wires 101, and 102, so that if 85 is in contact with 86 and 97, and button 98 has been pushed, a circuit for valve 66 is formed as follows: one terminal of the battery 68, wire 81, valve 66, wires 80, 104, 105, 106, 107 and 101, connector 103, wire 102, contact 97, connector 85, contact 86, wires 100 and 73, contact 72, connector 71, contact 70 and wire 69 to the other terminal of the battery 68. Current flowing in the above-traced path maintains the energization of valve 66. It should be noted however that the circuit last traced depends for its continuity both upon 85 connecting 86 and 97, and upon 103 connecting 101 and 102. The connection between 86 and 97 by 85 is made inevitable by the forward movement of the train, and is a connection which corresponds with the position of the permissible speed indicator 59. The button 98 must be manually operated by the driver, and this fact obliges the driver to maintain his observation of the position of the red pointer 59, because when that pointer indicates just a little higher than fifty miles per hour, it indicates that the connector 85 is about to move from contact 87 to contact 97, and that unless button 98 is pushed the valve 66 will become deenergized. The necessity for the driver manipulating button 98 also obliged the driver to maintain watch of the actual speed indicating hand 62, because the button 98 cannot be depressed sufficiently to make contact between wires 101 and 102 unless the actual speed of the vehicle has been reduced to fifty miles per hour or less as will presently appear. Consequently, if the driver would maintain control of the train or vehicle and prevent an automatic application of the air brakes thereof, he must, upon passing a signal 6, into a caution block, watch his actual speed pointer 62 and his permissible speed indicator 59 and always maintain the pointer 62 advanced in a counter clock-wise direction more than pointer 59, otherwise

when pointer 59 closely approaches the indication of fifty miles per hour upon the dial, he will be unable to depress button 98 because the actual speed pointer 62 will indicate more than 50 miles per hour and the train will actually be moving at more than 50 miles per hour. The reason the button 98 cannot be depressed if the vehicle is moving at more than fifty miles per hour is because as perhaps best shown in Fig. 3, the button is the termination of a rod 108, which passes through a plate 109 and bears a plunger 110, which is positioned over the plate 111. This plate 111 is formed with slots 112, 113, 114 and 115 which slots are in line with buttons 98, 117, 118 and 119 so that the slots may be brought underneath the plungers as 110 upon a proper movement of the plate 111. This proper movement of plate 111 is given by the fly-ball device G by means of rod 82 attached to one end of lever 121, which is pivoted at 122. The end of the lever 121 not connected to rod 82 is connected through a resilient connection, designated as a whole by 123, to the plate 111. In the position shown for the fly-ball device in Fig. 2, in which it is assumed that the vehicle is moving at sixty miles per hour, the plate 111 is in the position as shown, but as the speed of the train is decreased, as it should be on entering a caution block, that is, the section in advance of signal 6, the plate 111 will be moved in the direction of the arrow E, and the connections are such that when the actual speed of the train has decreased to fifty miles per hour, the slot 112 will have come under the plunger 110 so that the plunger 110 may be depressed, and upon being depressed will be maintained depressed by the spring-pressed plunger 124, moving into the cavity 125 of the plunger 110.

It should now be understood that a train upon passing signal 6 as shown in Fig. 1, would have its electropneumatic valve, as 66, maintained energized during a certain distance traveled by the train by reason of 85 connecting 86 and 87, and that upon the completion of that distance 85 would connect 86 and 97, and that when 85 does connect 86 and 97, the train has advanced so far into the caution block that it is necessary for safety that its speed be not above fifty miles per hour; consequently, it has been provided that unless the driver has reduced the actual speed of the train to fifty miles an hour or less, he cannot push the button 98, thereby connecting wires 101 and 102, and thereby completing another circuit for the valve 66 through the contact 97. The result is that the driver of a train passing the signal 6 under the conditions as outlined must immediately begin to reduce his speed, so that when he has traveled such a distance into the caution block 85 connects 86 and 97, his train will be

moving at not more than fifty miles per hour, so that he can push buttons 98, thereby completing the circuit for the valve 66, through wires 101 and 102 and in the same way as the train proceeds through the block, member 85 breaks contact with 97 and makes contact with 126, and at that moment or just before, the button 117 must be depressed in order to connect wires 127 and 128, but this cannot be done unless the speed of the train has been reduced to forty miles per hour or less, and as the train proceeds 85 breaks contact with 126, and makes contact with 129, at which time or just before the button 118 must be depressed to close contact between wires 130 and 131, but this cannot be done unless the actual speed of the train has been reduced to thirty miles per hour and as the train proceeds 85 breaks contact with 129 and makes contact with 132, at which time or just before, button 119 must be pressed to make contact between wires 133 and 134, but this button 119 cannot be depressed unless the speed of the train has been reduced to twenty miles per hour or less, and as the train proceeds 85 breaks contact with 132 so that the circuit for valve 66 through 86 is thereby broken, but at the time of 85 breaking contact with 132 or just before another circuit is formed as follows: battery 68, wire 69 and contact 120, connector 135, contact 137, wires 136, 104 and 80, valve 66 and wire 81 to the battery 68.

The connector 135 and contacts 120 and 137 are so positioned and arranged that a circuit is formed therethrough at all times when the speed of the vehicle does not exceed say 10 miles per hour.

It is thus seen that as the train proceeds through the caution block the connector 85 sweeps over the contacts 87, 97, 126, 129 and 132, and that as it successively engages these different contacts, buttons 98, 117, 118 and 119 must be successively depressed; but that these buttons cannot be depressed unless the actual speed of the train has been reduced to the proper amount so that it is proper to allow them to be depressed. It should also be observed that the ability of the driver to depress any one of the several buttons is always known to him by his observation of the position of the actual speed pointer 62.

The circuits controlled by buttons 117 to 119 inclusive are similar in all respects to the circuit controlled by button 98, and it is therefore deemed unnecessary to trace each of these circuits, as their construction is apparent from the drawing, and their function is apparent from the description of the circuit controlled by button 98.

The means by which the buttons as 98 and 117 to 119 inclusive close the contacts between the wires is shown by Fig. 3, in which

103 as designated in Fig. 2 is shown as a metallic member which, upon being depressed, engages one, 133, of two adjacent similar contacts, to which wires 101 and 102 are connected.

Between the plate 111 and the lever 121 is a resilient connection 123, comprising a member 139 connected to lever 121 and a member 140 connected to plate 111. Each 10 of these members 139 and 140 have outstanding projections, as 141 and 142, on 139, and 143 and 144 on 140; and between these outstanding projections is an expanded spring 145 of such size that it will transmit motion 15 from lever 121 to plate 111, under ordinary conditions without either compressing or extending, but if the actual speed of the train is increased after a button as 98 has been depressed so that a plunger as 110 rests 20 in a slot 112 of the plate 111, then when due to an increase in speed the plate 111 causes the end of the slot 112 to contact with the plunger as 110, the resilient connection is such that relative movement is allowed between lever 121 and plate 111, so as not to shear the plunger 110.

The parts are so proportioned as shown in Fig. 2 that when connector 85 reaches and passes the extreme upper end of 132 as 30 viewed in Fig. 2, the cut-away portion 61 of the worm wheel 44 is underneath the worm 43, so that no further movement of 85 takes place and the train may proceed indefinitely at not more than, say, ten miles 35 per hour, which permissible speed, as before pointed out, will be continuously indicated by the red hand 59, and will be allowed by reason of contacts 120 and 137.

After the mechanism on a vehicle as 40 shown by Fig. 2 has gone through the operations as herein before described, the red pointer 59 will constantly indicate a permissible speed of ten miles per hour until the vehicle passes over an electromagnetic 45 device in the trackway as 9 which will cause a magnetic flux through the iron core 27 on the vehicle. At that time as hereinbefore described the electromagnet 27 will be energized, worm 43 will be lifted, worm wheel 50 44 will return to its initial position as shown in Fig. 2, and the rack bar 57 will also return to its initial position as shown in Fig. 2, and by so doing will move the member 146 to the position as shown in Fig. 2, so 55 that the wedged members 147, as perhaps best shown in Fig. 3, will contact with the upturned ends, as 148, of the rods, as 149, attached to plunger 124, and will move the rods, as 149, and plunger 124 to the left as 60 viewed in Fig. 3, so that the plunger 124 will be withdrawn from the cavity 125 in the plunger 110 and then the spring 150 will force the button 98 and its attached parts to the original undepressed position. 65 This same action will take place with all

of the buttons 117 to 119 inclusive, so that they will all return to normal undepressed position.

From the above description it will be seen that applicant has provided a train control 70 device which is truly semi-automatic in its operation, because if a vehicle equipped with a system in accordance with applicant's invention, passes a full clear signal, it is necessary for the driver to actually perform a 75 manual operation or else the apparatus will so act as to cause and impose a constantly decreasing permissible speed, so that with a system constructed in accordance with applicant's invention, if a driver should fall 80 dead just before reaching a clear signal, a gradually decreasing permissible speed will be immediately imposed upon the vehicle and it would not proceed perhaps past a dozen clear signals before it would be 85 brought to a stop by reason of encountering a danger signal. This is very important because signals as a rule only indicate the 90 existence of temporary hazards, that is, the existence of movable trains on the trackway 95 ahead, but there are many permanent hazards on the trackway the existence of which is not reflected by the signals or by the track circuits, and these permanent hazards, such as curves and grades, require 100 for safe operation a maximum permissible speed sometimes very much lower than the maximum permissible speed allowed at other points on the roadway, so that it is essential that a train should be brought down in speed when passing these permanent hazards even though the signal indicates full 105 clear. This applicant's system provides for this, because as soon as the driver becomes incapacitated or fails to perform a simple 110 manual operation, the train has imposed upon it a gradually decreasing maximum permissible speed even under full clear conditions, so that for this reason applicant has denominated his system a semi-automatic 115 system, because it requires the cooperation both of the driver and the trackway device to pass even a full clear signal without having a gradually decreasing maximum permissible speed imposed.

It is also apparent that in accordance with applicant's system, after a vehicle has entered what has been called a caution block or section in which a gradually decreasing maximum permissible speed should be imposed, that manual operations of the driver are required after the train has traversed successive distances along the trackway, so that the driver must not only gradually reduce the speed of its train in accordance 120 with the predetermined curve of speeds, but he must also perform certain manual operations in order to proceed continuously even if he has reduced his speed to the proper amount, so that again for this reason also 125 130

applicant has denominated his system a semi-automatic system.

Applicant, of course, does not intend to restrict the positioning of the trackway device, as 9, to the exact positions, as shown, as the positioning of these devices would depend upon the layout of the signals and track, but whatever the positioning it must be such that it will properly co-operate with applicant's train device, so that a train will always be brought to a minimum low speed or stopped before entering an occupied track section. Nor does applicant intend to restrict the use of track devices, as 9, to positions only at or closely adjacent to signals. Nor does applicant mean to convey the impression that the ordinary type of signal is at all necessary with his invention.

Although I have particularly described the construction of one physical embodiment of my invention and explained the operation and principle thereof, nevertheless I desire to have it understood that the form selected is merely illustrative but does not exhaust the possible physical embodiments of the idea of means underlying my invention.

What I claim as new and desire to secure by Letters Patent of the United States is:

1. In a semi-automatic train control device, in combination; a vehicle; a roadway; means on the vehicle including manually operable means co-operating with means on the roadway for allowing the vehicle to travel at not above a predetermined maximum speed for a given length of travel; means including manually operable devices for thereafter allowing the vehicle to travel for a given distance at a gradually reducing maximum speed down to a predetermined minimum speed and means for thereafter allowing the vehicle to travel indefinitely at not above the said predetermined minimum speed.

2. In a semi-automatic train control device, in combination; a vehicle; a roadway; means on the vehicle, including manually operable means, cooperating with means on the roadway for indicating a maximum permissible speed for the vehicle, a gradually decreasing permissible speed and a permissible minimum speed.

3. In a semi-automatic train control, in combination; a vehicle; a roadway; means on the roadway for generating a magnetic flux; a partial circuit on the vehicle including a manually operable biased to open position circuit controller and a receiving coil and an electro-magnet whereby a current is generated in the partial circuit and the elec-

tro-magnet energized when the receiving coil passes over the roadway means when generating a magnetic flux if the circuit controller is being operated manually; an armature controlled by the electro-magnet and means controlled by the armature controlling the vehicle.

4. The method of train control which consists in obliging the train driver to take action at regularly recurring intervals along the trackway in order to proceed at a predetermined maximum speed and upon approaching a danger point to take action at regularly recurring shorter intervals in order to proceed at gradually reducing speeds down to a permissible minimum speed and to then proceed indefinitely at such minimum speed without taking further action.

5. In a semi-automatic train control in combination: a vehicle; a roadway; a vehicle control device on the vehicle; means on the vehicle for causing said device to operate to decrease the speed of the vehicle if the speed exceeds a predetermined maximum; means for causing said device to operate to decrease the speed of the vehicle if the vehicle exceeds certain predetermined sub-maximum speeds including devices which must be manually operated after certain predetermined lengths of travel of the vehicle and means for preventing the operation of said device to decrease the speed of the vehicle regardless of its length of travel if the speed of the vehicle is below a predetermined minimum.

6. The method of train control which consists in obliging the train driver upon approaching a danger point to take action at regularly recurring substantially short intervals in order to proceed at gradually reducing speeds down to a permissible minimum speed and to then proceed indefinitely at such minimum speed without taking further action.

7. In a semi-automatic train control in combination: a vehicle; a roadway; a vehicle control device on the vehicle; means for causing said device to operate to decrease the speed of the vehicle if the vehicle exceeds certain predetermined sub-maximum speeds, including devices which must be manually operated after certain predetermined lengths of travel of the vehicle and means for preventing the operation of said device to decrease the speed of the vehicle regardless of its length of travel thereafter if the speed of the vehicle is below a predetermined minimum.

LYMAN E. DODGE.
